UNITED STATES PATENT OFFICE.

CHARLES C. WICKWIRE, OF CORTLAND, NEW YORK.

PUMPING MECHANISM.

952,594.

Specification of Letters Patent. Patented Mar. 22, 1910.

Application filed March 1, 1909. Serial No. 489,498.

To all whom it may concern:

Be it known that I, CHARLES C. WICKWIRE, a citizen of the United States, residing at Cortland, in the county of Cortland and State of New York, have invented certain new and useful Improvements in Pumping Mechanism, of which the following is a specification.

My present invention relates to a pumping mechanism which is particularly intended for use in connection with suction cleaning devices of that general type in which air is drawn in at a nozzle so as to pick up adjacent dust, then passes through a dust separator where the dust is retained, and finally passes through pumping mechanism back to the atmosphere.

The invention resides in a novel construction and combination of parts whereby I secure a foot operated bellows easily operated, simple and strong in construction and easily carried about. It is suited to any purpose where such a pumping mechanism is desirable, but I illustrate it as applied to a suction cleaning machine, that being the use to which I propose to put it. In connection with the pump I illustrate a dust separating device which is described and claimed in my application Serial No. 504,816, filed June 28, 1909.

The pumping device will be described in connection with the accompanying drawings, wherein,

Figure 1, is a perspective view of a cleaning device showing my improved pumping mechanism; Fig. 2, is a sectional elevation on the line *b*—*b* of Fig. 1; and Fig. 3 is a plan view of the apparatus, certain parts being omitted or shown in section for purposes of clearness.

Like numerals refer to like parts through the drawings.

Referring to the drawings, 1 is a frame or baseboard on which the apparatus is mounted. This frame I prefer to make of wood and of the form shown, the openings 2 and 3 being provided for lightness and for other purposes, which will later be explained. Rigidly attached to this baseboard are the brackets 5 carrying the pivot rod 6 on which are independently hinged the bellows tops 7 and 8. These bellows tops which have an extension or projection past said pivot rod 6, forming treadles 9 and 10, so that the depression of a treadle causes the elevation of a bellows top and vice versa. To keep

the bellows tops depressed, and consequently the treadles in an elevated position, springs 11 are provided, one for each bellows, coiled around the pivot rod 6 and having one end bearing downwardly upon the bellows tops and the other end bearing downwardly on the frame at the opposite side of the pivot rod. If it be for any reason desirable, separate pivot rods may be provided for each bellows so that the relative position of the treadles may be arranged conveniently. The openings 2 and 3 mentioned as formed in the baseboard 1 are so located as to lie under the treadles 9 and 10, and thus allow a deeper depression of the treadles for a given height of the apparatus.

As illustrated particularly in Fig. 2 each bellows top is provided with an outwardly opening flap valve 12, while within the bellows chambers are inwardly opening valves 13. These valves 13 admit air from the ducts 14 and 15, one for each valve, leading from a main duct 16. These ducts 14, 15 and 16 I prefer to form by boring through the base-board 1, the wood of the baseboard forming the walls of the ducts, but an equivalent system of piping might be used. As a convenient method of attaching the duct 16 to the device from which air is to be exhausted, in this case the dust separator drum 21, I make use of an elbow consisting of a wooden block with suitably bored channels carrying a nipple 18. A piece of rubber hose 19 is used to connect the nipple 18 to nipple 20, entering the separator drum 21. A similar connection might be used to connect the pumping mechanism to any other device from which air is to be exhausted.

The details of the dust separator 21 will not be described, but as is obvious from the drawings, the separator 21 is connected by a flexible tube 31 to the tubular handle 32 of the cleaning nozzle 33, which last is of the usual type. The path of the air is then through the nozzle, tube and separator in the order stated, then through the duct 16 to the bellows and back to the atmosphere through the valves 12.

The method of operating the pumping mechanism will now be described.

The operator stands on the treadles 9 and 10, and by treading thereon sets the bellows tops into vibration. The fact that the bellows tops are hinged independently of each other allows the operator to assume any sequence of movements which he may prefer,

or to use only one bellows at will, and by permitting changes in the movement, enables him to pump longer periods without becoming excessively tired. Bellows mechanism have hitherto been known in which the operator stood upon the bellows tops and operated the bellows by treading upon said bellows tops, but in all such devices the mechanism has been such that the depression of one bellows top caused the elevation of the other, and the motion of the tops was therefore constrained and subject to no variation except in the speed. The resulting motion is unnatural and tiring and the position of the feet not so satisfactory as may be had by the use of my construction. I therefore lay great stress on the independence of the treadles in my structure and on my ability to place them in any position relative to each other which may seem desirable. It will also be noted that the form of frame adopted for the mechanism allows the convenient attachment of the dust separator, so that the whole forms a compact mechanism readily portable and easily stored. It is also obvious that the form of the bellows allows one person to do the pumping with his feet, while using his hands to manipulate the cleaning nozzle or such other devices as might require his attention.

Having thus described my invention, what I claim is:—

1. A pumping mechanism comprising in combination, a base frame; fulcra on the frame; individually operable bellows mounted on the fulcra at opposite sides thereof;

treadles projecting past the fulcra in opposite directions from their respective bellows and forming extensions thereof, said treadles being out of alinement with each other; and springs to hold said bellows in a closed position.

2. In a pumping mechanism, the combination of a base having a pair of non-alined openings formed therein and adapted to rest flat upon a floor; a treadle located over each opening; and bellows arranged upon the top of the base opposite each treadle, and operatively connected thereto.

3. In a pumping mechanism the combination with a base a pair of non-alined treadles fulcrumed upon the top of said base and extending in opposite directions from their fulcra, the base being formed with an opening beneath each treadle; and a bellows arranged upon the base opposite each treadle, the top of each bellows being rigidly connected to a treadle.

4. In a pumping mechanism the combination of a base; a pair of non-alined treadles fulcrumed upon the top of said base and extending in opposite directions from their fulcra; and a bellows arranged upon the base opposite each treadle, the top of each bellows being rigidly connected to a treadle.

In testimony whereof I have signed my name to this specification in the presence of two subscribing witnesses.

CHARLES C. WICKWIRE.
